UNITED STATES PATENT OFFICE.

JAMES F. TRUMBO, OF PUEBLO, COLORADO.

FLOUR-SIFTER.

1,357,129.

Specification of Letters Patent. Patented Oct. 26, 1920.

Application filed May 25, 1920. Serial No. 384,061.

To all whom it may concern:

Be it known that I, JAMES F. TRUMBO, a citizen of the United States, residing at Pueblo, in the county of Pueblo and State 5 of Colorado, have invented certain new and useful Improvements in Flour-Sifters, of which the following is a specification.

This invention relates to household sifters and more particularly for flour and the like 10 of the type which may be held and actuated by one hand.

The object of the invention is to provide a one hand sifter of this character so constructed that all of the parts will operate with substantially more friction and in 15 which the gripping action which operates the agitator is easy requiring very little effort on the part of the user.

Another object is to so construct such a 20 sifter as to cause a uniform flow of the material being sifted at each stroke of the agitator and which will quickly sift the entire contents of the sifter.

Another object is to provide a sifter of 25 this character which may be cheaply manufactured and sold at a price within the reach of everybody.

With these and other objects in view, the invention consists in certain novel features 30 of construction as hereinafter shown and described and then specifically pointed out in the claims, and in the drawings illustrative of the preferred embodiment of the invention.

35 In the accompanying drawing:

Figure 1 represents a perspective view taken from the rear of a sifter constructed in accordance with this invention.

Fig. 2 is a side elevation with parts broken 40 out and in section, and,

Fig. 3 is a transverse section taken on the line 3—3 of Fig. 2.

In the embodiment illustrated the sifter embodying this invention comprises a cylindrical container 1 open at both ends as is 45 customary with sifters of this character and having the usual pouring lip 2. A hollow handle 3 projects laterally from the rear wall thereof and a shaft 4 extends transversely across the container 1 and longitudinally through the handle 3 with its outer end headed as shown at 3' to hold it against longitudinal movement in one direction. Mounted on the shaft 4 within the container 50 55 1 is an agitator 5 composed of a plurality of longitudinally curved spaced rods or wires

6 any desired number of which may be employed three being here shown. These wires are connected at their ends by collars 7 which are carried by the shaft 4 adjacent 60 the opposed side walls of the container 1 as is shown clearly in Fig. 2. A screen 8 is arranged in the container 1 below the agitator in close proximity thereto and is curved to conform to the curvature of the agitator 65 to provide for a scraping movement of the agitator over the screen to effect sifting of the material and force the material out through the screen in the ordinary way.

Fixed to the shaft 4 adjacent the outer 70 wall of the container is a gear 9 which meshes with a vertically reciprocatory rack bar 10 mounted in a tube 11 secured to the outer face of the container 1, this tube 11 has an opening 12 in one side thereof so that 75 the teeth of the rack bar may mesh with the gear 9. This rack bar as shown is in the form of a rod having a laterally extending arm 13 at its lower end. An extension 14 projects forwardly from the free end of the arm 13 and has its terminal mounted in a depending bracket 15 carried by the outer end of the handle 3. This bracket 15 as here shown is in the form of a wire loop 80 although obviously it may be of any other 85 desired construction.

The arm 13 of the rack bar lies adjacent the outer face of the container 1 while its extension 14 projects radially from said container in a plane below and parallel with 90 the handle 3 and has mounted thereon a sleeve 16 preferably constructed of wood or other suitable material to provide for gripping of the device without injury to the hand of the user.

The inner end of the handle 3 carries a housing 17 to form a chamber in which the gear 9 operates, the inner end of the handle 3 operating to hold the gear in operative position on the shaft 4 as is shown clearly 100 in Fig. 2.

In the use of this device the roller or sleeve 16 and the handle 3 are gripped by hand of the user and by compressing the roller 16 its journal 14 will move inwardly 105 in the loop-shaped bracket 15 thereby causing the agitator to move a partial revolution over the screen 8. A coil spring 18 connects the lower end of the rack bar 11 with the container and operates to turn the 110 rack bar after it has been forced upwardly by pressure exerted on the member 16. It

will thus be obvious that the compression of the member 16 will operate to move the rack bar upwardly in the tube 11 and owing to the intermeshing engagement of its teeth 5 with the gear 9 will rotate said gear and turn the shaft 4 and as soon as pressure is released on the member 16 the spring 18 will return the rack to normal position.

The oscillatory movement imparted to the 10 agitator 5 will effect an even flow of material through the screen.

The preferred embodiment of the invention is disclosed in the drawings and set forth in the specification, but it will be 15 understood that any modification within the scope of the claims may be made in the construction without departing from the principle of the invention or sacrificing any of its advantages.

20 What is claimed is:

1. A sifter of the class described comprising a container having a screening element therein, an agitator movable over said element, a hollow handle projecting laterally 25 from said container, a shaft extending transversely through said container and longitudinally through said handle, said agitator being fixed to said shaft, a gear fixed to

said shaft outside said container, a tubular casing mounted on said container adjacent 30 said gear and having an opening in its side wall facing the gear, a rack bar reciprocable in said casing and meshing with said gear, an arm carried by said bar extending parallel with and spaced from said handle, a spring connected to retract said bar, said arm thereof being compressible against the tension of said spring to project the bar. 35

2. In a sifter of the class described, a container having a screening element therein, 40 an agitator in said container above said element, actuating means for said agitator comprising a vertically reciprocable rack having an L-shaped extension projecting laterally from one end, the short arm of 45 said extension being connected with said rack, and its long arm extended outwardly from the container, a coiled spring connected with the container and with said rack to move said rack in one direction, and a 50 handle extending laterally from the container parallel with the long arm of said rack extension.

In testimony whereof I affix my signature hereto.

JAMES F. TRUMBO.
